WATER FILTER

Samuel J. Mann, Englewood, N.J., assignor to
Westinghouse Electric Corporation

Filed Sept. 15, 1971, Ser. No. 180,932

Term of patent 14 years

Int. Cl. D23—01

U.S. Cl. D23—4

FIG. 1

FIG.2

FIG.3

FIG.4

FIG. 1 is an isometric view of a water filter embodying my new design showing the top, one side, and front;

FIG. 2 is a top plan view thereof;

FIG. 3 is a front elevational view thereof, the rear being plain and unornamented; and

FIG. 4 is an elevational view taken from the side opposite that shown in FIG. 1.

I claim:

The ornamental design for a water filter, as shown and described.
